CLAIM

The ornamental design for a camera, as shown and described.

DESCRIPTION

FIG. 1 is a front elevation view of a camera showing our new design;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front, left, and top perspective view thereof;

FIG. 8 is a back, right, and bottom perspective view thereof; and,

FIG. 9 is a back, right, and top perspective view thereof.

The broken lines depict portions of the article that form no part of the claimed design.

1 Claim, 9 Drawing Sheets
